UNITED STATES PATENT OFFICE.

JOHN T. W. RUDESILL, OF EAST ST. LOUIS, ILLINOIS, ASSIGNOR TO
DAMASCUS BRAKE BEAM COMPANY, OF ST. LOUIS, MISSOURI, A
CORPORATION.

FINGER-GUARD CLIP FOR BRAKE-BEAMS.

SPECIFICATION forming part of Letters Patent No. 699,929, dated May 13, 1902.

Application filed October 21, 1901. Serial No. 79,389. (No model.)

To all whom it may concern:

Be it known that I, JOHN T. W. RUDESILL, a citizen of the United States, residing in East St. Louis, in the county of St. Clair and State 5 of Illinois, have invented certain new and useful Improvements in Finger-Guard Clips for Brake-Beams, of which the following is a full, clear, and exact description, reference being had to the accompanying drawings, forming 10 part of this specification.

My invention relates to a finger-guard clip for use upon brake-beams in holding the finger-guards thereto in proximity to the brake-heads, the clip being of such construction 15 that it may be readily applied to the brake-beam or disconnected therefrom.

The invention consists in features of novelty hereinafter fully described, and pointed out in the claims.

20 Figure I is a perspective view of a brake-beam equipped with my clips. Fig. II is an enlarged detail top view of one end of the brake-beam with the clip applied thereto. Fig. III is a cross-sectional view taken on line 25 III III, Fig. II.

1 designates a brake-beam, shown of I form and having brake-heads 2 attached thereto.

3 designates a finger-guard, which it is common to attach to brake-beams in a position 30 beside the brake-heads to limit the endwise movement of the brake-beams while hanging suspended beneath a car. The clip by which said finger-guard is attached to the brake-beam comprises a body 4, having a tubular 35 boss 5, in which the head end of the finger-guard is seated and held to the face of the brake-beam 1.

6 is a rearwardly-extending arm that extends from the body 4 over the top edge of 40 the upper flange of the brake-beam, then downwardly, and onto the upper surface of the central portion of the brake-beam, so as to lie flat upon said central portion. The arm 6 is apertured to receive an eyebolt 7, 45 to which the suspension-chain of the brake-beam is attached, and said eyebolt passes through said arm and the central portion of the brake-beam to hold the clip firmly in po-

sition on the brake-beam. At the lower edge of the body 4 is a lip 8, that extends rearwardly beneath the lower flange of the brake-beam and serves to hold the clip at its lower edge to the brake-beam and at the same time strengthen the clip and its connection to the 50 brake-beam.

The clips are readily applied to the brake-beam by slipping them thereonto before the insertion of the eyebolts 7, and when said eyebolts have been inserted the clips are securely held from escape. When it is desired 60 to remove the clips for any reason, the eyebolts are first removed, and the clips can then be readily disconnected from the brake-beam by slipping or swinging them off of the beam, as will readily appear, there being sufficient 65 spring in the clip (which is preferably of malleable iron) to allow the lip 8 to pass from beneath the lower flange of the beam.

By having the head of the finger-guard 3 fit up against the face of the beam it is held 70 from inward movement and its head prevents it from moving outwardly.

I claim as my invention—

1. The combination of a brake-beam, a clip fitted against the beam and having an arm 75 extending rearwardly therefrom and resting on the body of the beam, an eyebolt for connecting the arms to the beam, and a finger-guard fitting in a socket formed in the clip and the inner end of which bears against the 80 beam, substantially as set forth.

2. A brake-beam having a flange and a web, a clip fitting against the face of the flange and having an arm passing over the upper edge of the flange and seated upon said web, and 85 having a clip fitting beneath the lower edge of the flange, an eyebolt connecting the arms of the clip to the web of the beam, and a finger-guard fitting in a socket formed in the clip and the inner end of which is provided 90 with a head that bears against the face of the flange of the beam, substantially as set forth.

JOHN T. W. RUDESILL.

In presence of—

W.M. RODENBERGER,
L.G. SMITH.
